Bello

[57] ABSTRACT

The margins of the upper and lower faces at the edges of a shoe component, for example a thick platform, simultaneously are coated with a cement, notwithstanding differences in the thickness of the component along its edges, in order to permit the edges to be covered by a decorative strip, while being bonded to the component by the cement so provided. The machine for performing this coating process comprises a pair of cement wheels, between which the margins of the upper and lower faces of the component are advanced, the upper wheel applying cement to the upper margin and the lower wheel applying cement to the lower margin in association with a cement supply wheel that is partially immersed in a cement trough. One of the cement wheels is driven through a shaft that is fixed with respect to a drive motor. The other of the wheels is mounted for rotation on a shaft that is driven by the drive motor through a universal coupling.

MACHINE FOR APPLYING CEMENT TO SHOE COMPONENTS OR THE LIKE

BACKGROUND OF THE INVENTION

1. Field of the Invention

The present invention relates to the production of shoes and, more particularly, to the application of cement to the margins of shoe components, for example thick platforms, for the purpose of enabling their edges to be covered by decorative strips of fabric or the like. More particularly, the present invention relates to machines for the application of a fabric strip to a shoe component, particularly a platform, by wrapping the strip about the edge of the component in such a way that the margins of the strip are cemented to the marginal portions of the opposite faces of the platform. Such platforms typically are components of ladies' shoes.

2. The Prior Art

Difficulties have been encountered in applying such decorative fabrics to the edges of shoe components because of the varying thicknesses of the components from point to point along their peripheries. In consequence, movement between two cement applicator wheels operating simultaneously at opposite faces of a component must be tolerated. Prior devices for attempting such an operation have been unduly complex and expensive.

The primary object of the present invention is to provide, in a machine for coating the margins at opposite faces of a shoe component, a pair of cement wheels, between which the margins of the upper and lower faces of the component are advanced, the upper cement wheel being supplied with cement under gravity and the lower wheel being supplied with cement by a cement transfer wheel that is partially immersed in a cement supply. The upper cement wheel is driven by a shaft that is fixed with respect to a drive motor. The lower cement wheel is mounted for rotation on a shaft that is driven by the drive motor through a universal coupling. The cement transfer wheel and the lower cement wheel are geared together and journaled in a link which slides and pivots in such a way as to maintain a constant height of the cement transfer wheel in a cement trough notwithstanding motion of the lower cement wheel toward and from the upper cement wheel in consequence of different thicknesses of the component to which cement is being applied.

Other objects of the present invention will in part be obvious and will in part appear hereinafter.

The invention accordingly comprises the apparatus, together with its components and their interrelationships, which are exemplified by the present disclosure, the scope of which will be indicated in the appended claims.

BRIEF DESCRIPTION OF THE DRAWINGS

For a fuller understanding of the nature and objects of the present invention, reference is made to the accompanying detailed specification, which is to be taken into connection with the accompanying drawings, wherein:

FIG. 1 is a perspective view of a device embodying the present invention;

FIG. 1A shows the result of cementing a binding on an unfinished edge with the device of the present invention.

FIG. 2 is an enlarged perspective view of a portion of the device of FIG. 1;

FIG. 3 is a front view of the device of FIG. 1;

FIG. 4 is a side view of the device illustrated in FIG. 5 1;

FIG. 5 is an enlarged detail view, partly broken away, of the device of FIG. 1, illustrating a first phase of operation; and

FIG. 6 is an enlarged detail view, analogous to FIG. 10 5, illustrating a second phase of operation.

DETAILED DESCRIPTION OF THE PREFERRED EMBODIMENT

Generally, in the apparatus of FIG. 1, bands of cement

15 cement are applied to margins 10, 12 of ladies' shoe platform 14. The purpose of applying bands of cement 10, 12 is to enable the covering of the unfinished edge 26 of the platform with a decorative strip 28, which in various forms is composed of fabric, leather or other flexible

20 finished material (in another machine not forming part of the present invention). Upper cement band 20 is applied by an upper cement wheel 30 and lower cement band 22 is applied by a lower cement wheel 32. The peripheries of upper wheel 30 and lower wheel 32 are knurled so that they perform the dual functions of gripping the edge of the platform therebetween and carrying cement to the margins of its upper and lower faces. The shaft of wheel 32 extends outwardly to a support wheel 34, which rotates freely and acts as a rotating cantilever support for the portion of the platform that has not been gripped between cement wheels 30, 32. The periphery of cement wheel 30 is supplied with liquid cement under gravity from a cement container 36 through a channel 38. Cement is supplied to cement

25 wheel 32 by an intermediate pickup wheel 40, the lower portion of which is dipped at predetermined height into a trough 42 that is supplied with cement from a container 44. Containers 36, 44 are removably held in inverted condition in suitable holders 46, 48.

30 40 A base 50, including support plate 51, mounts containers 46, 48 together with all of the other components of the apparatus. These components include a motor 52, first and second belt drives 54, 56 and a transmission 58. Details of transmission 58 and its interconnection with the remaining components of the present apparatus now will be described.

45 As shown in FIG. 4, cement wheels 30, 32 are driven via a pulley 60 through a shaft 62 which is journaled on base 50. On shaft 62 is a gear 64 which meshes with a gear 66. Gear 66 is keyed to a shaft 68 that projects forwardly through transmission 58 to upper cement wheel 30 so that the axis of cement wheel 30 is fixed with respect to base 50. On the other hand, cement wheel 32 is keyed to a shaft 70 which is journaled in a block 72 for transverse constraint in a vertical slot 47. Block 72 is part of a casting, other portions of which, also designated 72, are shown in other figures. Shaft 70 is connected to shaft 62 by a universal coupling 76 which permits rotation of shaft 70 notwithstanding the position of block 72 within slot 47 and notwithstanding the consequent position of cement wheel 32 with respect to cement wheel 30. Fixed to transmission 58 is a plate 78 which is provided with a horizontal slot 80. The shaft 82 of intermediate pickup wheel 40 extends into and through slot 80. Shaft 70 of cement wheel 32 and shaft 82 of cement wheel 40 both are journaled in a link

55 60 65 84, by which a pair of gears 86, 88 keyed to shafts 70, 82, respectively, are rotated. Gears 86, 88 are keyed to a shaft 90 which is journaled in a block 92. Block 92 is journaled in a slot 94 in a casting 96 which is part of a casting 98. Casting 98 is journaled in a slot 100 in a casting 102 which is part of a casting 104. Casting 104 is journaled in a slot 106 in a casting 108 which is part of a casting 110. Casting 110 is journaled in a slot 112 in a casting 114 which is part of a casting 116. Casting 116 is journaled in a slot 118 in a casting 120 which is part of a casting 122. Casting 122 is journaled in a slot 124 in a casting 126 which is part of a casting 128. Casting 128 is journaled in a slot 130 in a casting 132 which is part of a casting 134. Casting 134 is journaled in a slot 136 in a casting 138 which is part of a casting 140. Casting 140 is journaled in a slot 142 in a casting 144 which is part of a casting 146. Casting 146 is journaled in a slot 148 in a casting 150 which is part of a casting 152. Casting 1037 is journaled in a slot 1038 in a casting 1039 which is part of a casting 1040. Casting 1040 is journaled in a slot 1041 in a casting 1042 which is part of a casting 1043. Casting 1043 is journaled in a slot 1044 in a casting 1045 which is part of a casting 1046. Casting 1046 is journaled in a slot 1047 in a casting 1048 which is part of a casting 1049. Casting 1049 is journaled in a slot 1050 in a casting 1051 which is part of a casting 1052. Casting 1052 is journaled in a slot 1053 in a casting 1054 which is part of a casting 1055. Casting 1055 is journaled in a slot 1056 in a casting 1057 which is part of a casting 1058. Casting 1058 is journaled in a slot 1059 in a casting 1060 which is part of a casting 1061. Casting 1061 is journaled in a slot 1062 in a casting 1063 which is part of a casting 1064. Casting 1064 is journaled in a slot 1065 in a casting 1066 which is part of a casting 1067. Casting 1067 is journaled in a slot 1068 in a casting 1069 which is part of a casting 1070. Casting 1070 is journaled in a slot 1071 in a casting 1072 which is part of a casting 1073. Casting 1073 is journaled in a slot 1074 in a casting 1075 which is part of a casting 1076. Casting 1076 is journaled in a slot 1077 in a casting 1078 which is part of a casting 1079. Casting 1079 is journaled in a slot 1080 in a casting 1081 which is part of a casting 1082. Casting 1082 is journaled in a slot 1083 in a casting 1084 which is part of a casting 1085. Casting 1085 is journaled in a slot 1086 in a casting 1087 which is part of a casting 1088. Casting 1088 is journaled in a slot 1089 in a casting 1090 which is part of a casting 1091. Casting 1091 is journaled in a slot 1092 in a casting 1093 which is part of a casting 1094. Casting 1094 is journaled in a slot 1095 in a casting 1096 which is part of a casting 1097. Casting 1097 is journaled in a slot 1098 in a casting 1099 which is part of a casting 1100. Casting 1100 is journaled in a slot 1099 in a casting 1100 which is part of a casting 1101. Casting 1101 is journaled in a slot 1102 in a casting 1103 which is part of a casting 1104. Casting 1104 is journaled in a slot 1105 in a casting 1106 which is part of a casting 1107. Casting 1107 is journaled in a slot 1108 in a casting 1109 which is part of a casting 1110. Casting 1110 is journaled in a slot 1111 in a casting 1112 which is part of a casting 1113. Casting 1113 is journaled in a slot 1114 in a casting 1115 which is part of a casting 1116. Casting 1116 is journaled in a slot 1117 in a casting 1118 which is part of a casting 1119. Casting 1119 is journaled in a slot 1120 in a casting 1121 which is part of a casting 1122. Casting 1122 is journaled in a slot 1123 in a casting 1124 which is part of a casting 1125. Casting 1125 is journaled in a slot 1126 in a casting 1127 which is part of a casting 1128. Casting 1128 is journaled in a slot 1129 in a casting 1130 which is part of a casting 1131. Casting 1131 is journaled in a slot 1132 in a casting 1133 which is part of a casting 1134. Casting 1134 is journaled in a slot 1135 in a casting 1136 which is part of a casting 1137. Casting 1137 is journaled in a slot 1138 in a casting 1139 which is part of a casting 1140. Casting 1140 is journaled in a slot 1141 in a casting 1142 which is part of a casting 1143. Casting 1143 is journaled in a slot 1144 in a casting 1145 which is part of a casting 1146. Casting 1146 is journaled in a slot 1147 in a casting 1148 which is part of a casting 1149. Casting 1149 is journaled in a slot 1150 in a casting 1151 which is part of a casting 1152. Casting 1152 is journaled in a slot 1153 in a casting 1154 which is part of a casting 1155. Casting 1155 is journaled in a slot 1156 in a casting 1157 which is part of a casting 1158. Casting 1158 is journaled in a slot 1159 in a casting 1160 which is part of a casting 1161. Casting 1161 is journaled in a slot 1162 in a casting 1163 which is part of a casting 1164. Casting 1164 is journaled in a slot 1165 in a casting 1166 which is part of a casting 1167. Casting 1167 is journaled in a slot 1168 in a casting 1169 which is part of a casting 1170. Casting 1170 is journaled in a slot 1171 in a casting 1172 which is part of a casting 1173. Casting 1173 is journaled in a slot 1174 in a casting 1175 which is part of a casting 1176. Casting 1176 is journaled in a slot 1177 in a casting 1178 which is part of a casting 1179. Casting 1179 is journaled in a slot 1180 in a casting 1181 which is part of a casting 1182. Casting 1182 is journaled in a slot 1183 in a casting 1184 which is part of a casting 1185. Casting 1185 is journaled in a slot 1186 in a casting 1187 which is part of a casting 1188. Casting 1188 is journaled in a slot 1189 in a casting 1190 which is part of a casting 1191. Casting 1191 is journaled in a slot 1192 in a casting 1193 which is part of a casting 1194. Casting 1194 is journaled in a slot 1195 in a casting 1196 which is part of a casting 1197. Casting 1197 is journaled in a slot 1198 in a casting 1199 which is part of a casting 1200. Casting 1200 is journaled in a slot 1199 in a casting 1200 which is part of a casting 1201. Casting 1201 is journaled in a slot 1202 in a casting 1203 which is part of a casting 1204. Casting 1204 is journaled in a slot 1205 in a casting 1206 which is part of a casting 1207. Casting 1207 is journaled in a slot 1208 in a casting 1209 which is part of a casting 1210. Casting 1210 is journaled in a slot 1209 in a casting 1210 which is part of a casting 1211. Casting 1211 is journaled in a slot 1212 in a casting 1213 which is part of a casting 1214. Casting 1214 is journaled in a slot 1215 in a casting 1216 which is part of a casting 1217. Casting 1217 is journaled in a slot 1218 in a casting 1219 which is part of a casting 1220. Casting 1220 is journaled in a slot 1219 in a casting 1220 which is part of a casting 1221. Casting 1221 is journaled in a slot 1222 in a casting 1223 which is part of a casting 1224. Casting 1224 is journaled in a slot 1225 in a casting 1226 which is part of a casting 1227. Casting 1227 is journaled in a slot 1228 in a casting 1229 which is part of a casting 1230. Casting 1230 is journaled in a slot 1229 in a casting 1230 which is part of a casting 1231. Casting 1231 is journaled in a slot 1232 in a casting 1233 which is part of a casting 1234. Casting 1234 is journaled in a slot 1235 in a casting 1236 which is part of a casting 1237. Casting 1237 is journaled in a slot 1238 in a casting 1239 which is part of a casting 1240. Casting 1240 is journaled in a slot 1239 in a casting 1240 which is part of a casting 1241. Casting 1241 is journaled in a slot 1242 in a casting 1243 which is part of a casting 1244. Casting 1244 is journaled in a slot 1245 in a casting 1246 which is part of a casting 1247. Casting 1247 is journaled in a slot 1248 in a casting 1249 which is part of a casting 1250. Casting 1250 is journaled in a slot 1249 in a casting 1250 which is part of a casting 1251. Casting 1251 is journaled in a slot 1252 in a casting 1253 which is part of a casting 1254. Casting 1254 is journaled in a slot 1255 in a casting 1256 which is part of a casting 1257. Casting 1257 is journaled in a slot 1258 in a casting 1259 which is part of a casting 1260. Casting 1260 is journaled in a slot 1259 in a casting 1260 which is part of a casting 1261. Casting 1261 is journaled in a slot 1262 in a casting 1263 which is part of a casting 1264. Casting 1264 is journaled in a slot 1265 in a casting 1266 which is part of a casting 1267. Casting 1267 is journaled in a slot 1268 in a casting 1269 which is part of a casting 1270. Casting 1270 is journaled in a slot 1269 in a casting 1270 which is part of a casting 1271. Casting 1271 is journaled in a slot 1272 in a casting 1273 which is part of a casting 1274. Casting 1274 is journaled in a slot 1275 in a casting 1276 which is part of a casting 1277. Casting 1277 is journaled in a slot

82, respectively are retained in mesh. It is apparent that, as block 72 rises or falls within slot 47, shaft 82 advances or retracts in slot 80. In consequence, the axis of cement wheel 32 and the axis of cement wheel 30 always are perpendicular to a vertical line passing therethrough and the axis of intermediate pickup wheel 40 always is disposed along a specific horizontal line. In consequence, intermediate pickup wheel 40 always is positioned within the cement in trough 42 at the same height.

Various adjustments simply and efficaciously are made in accordance with the present invention. With reference to FIG. 3, normally link 84 is biased upwardly, so that cement wheel 32 is spring pressed toward cement wheel 30 by a helical spring 90 which extends between transmission box 58 on a lug on block 72. The orientation of link 84, in a counterclockwise direction as indicated in FIG. 3, is limited by a stop screw 95. The position of a skimming finger 59 on a skimming finger shaft 94 is controlled via block 96 to adjust film thickness. The position of block 96 is adjusted by a screw and spring arrangement 106, in which the screw freely projects through block 96 and is adjustably turned into a threaded bore in block 72 and the spring urges block 96 away from block 72. Skimming finger 59 may be forced to pivot against the bias of the spring when and if a large clump of cement is carried from cement supply 36 by cement wheel 30.

As shown, a pair of guide rollers 102, 104 are journaled in a pair of cantilever struts 106, 108 for purpose of limiting inward movement of the shoe component. Strut 108 is adjustably carried by a bracket 110 which has an upwardly extending portion that is bolted to transmission housing 58 and a horizontal portion (partly obscured in FIG. 2) to which strut 108 is bolted. Strut 106 is bolted to the horizontal portion of a bracket 112, the vertical portion of which is adjustably bolted to transmission housing 58. A skimming finger 59, which also is secured to shaft 94, removes excess cement from cement wheel 32.

OPERATION

In operation, the manually held platform is manipulated between cement wheels 30, 32 with its innermost edge abutting against guide rollers 102, 104 and its medial portion resting on support wheel 34. Cement is applied by cement wheels 30, 32 throughout the margins of the platform. During this procedure, as the thickness at the edge of the platform increases or decreases, cement wheel 32 is lowered or raised, respectively, while intermediate pickup wheel 40 is displaced along the horizontal in such a way that its level of immersion in the cement of trough 42 is maintained. During this procedure, the thickness of the cement coat at the under margin of the platform is determined by skimming finger 59. This adjustment is made by means of finger 96 and adjusting screw 98, the level of the cement being the natural result of the inverted cement container 44 which is communicating with trough 42. On the other hand, the amount of cement being applied by cement wheel 30 is determined by the position of channel 38 with respect to cement wheel 30 along the horizontal. This position is determined by a screw 114 which extends through a portion of transmission housing 58 and through a portion of container support 46. One end of the screw is positioned by a locked thumb nut 116 and the other end of the screw is positioned by an adjust-

able thumb nut 118 and a spring 120, extending between thumb nut 118 and a wall of transmission housing 58. Rotating thumb nut 118 determines the lateral position of container support 46 and consequently the rate of flow of cement from the container to cement wheel 30. Thus, at all times, pickup wheel 40 is immersed to a desired depth into the cement of trough 42 and lower cement wheel 32 is free to rise and fall in response to the varying thicknesses of the platform. Both cement wheels nevertheless are driven by the same motor, the upper cement wheel being driven by direct gearing and the lower cement wheel being driven by a universal coupling.

CONCLUSION

The present invention thus features a pair of cement wheels which are supplied with controlled amounts of cement by precisely adjustable components and which nevertheless are free to move with respect to one another in order to permit the application of cement simultaneously to the upper and lower margins at both faces of a platform of varying thickness. Since certain changes may be made in the present disclosure without departing from the scope of the invention herein, it is intended that all matter contained in the foregoing description or shown in the accompanying drawings be interpreted in an illustrative and not in a limiting sense.

What is claimed is:

1. An apparatus for applying cement to margins at opposite faces of a shoe component of differing thickness, said apparatus comprises a base, an electric motor fixed with respect to said base, a first journal fixed with respect to said base, a first shaft in said first journal and driven by said electric motor, a second journal constrained for motion with respect to said base in a first direction, a second shaft mounted for rotation in said second journal, a universal coupling connecting said electric motor and said second shaft, a first cement wheel keyed to said first shaft, a second cement wheel keyed to said second shaft, a third journal constrained for motion with respect to said base in a second direction, a third shaft in said third journal, a third cement wheel keyed to said third shaft, a link fixedly connecting said second journal and said third journal, resilient means connected between said base and said link in order to urge said second cement wheel toward said first cement wheel, a first cement supply communicating with said first cement wheel, a second cement supply communicating with said third cement wheel, said second cement wheel and said third cement wheel being geared together and in contact so that cement is transferred from said third cement wheel to said second cement wheel, whereby as said second wheel moves toward and away from said first cement wheel, the exposure of said third cement wheel to said second cement supply is maintained constant.
2. The apparatus of claim 1 wherein the rate of flow of cement to said first cement wheel is determined by adjusting the exposure of said first cement wheel to said first cement supply.
3. The apparatus of claim 1 wherein the rate of flow of cement to said second cement wheel is determined by adjusting a film control finger in association with said second cement wheel.
4. The apparatus of claim 1 wherein said first cement wheel and said second cement wheel are knurled.

5. The apparatus of claim 1 wherein a support wheel is mounted on said first shaft for free rotation.

6. The apparatus of claim 1 wherein a pair of guide rollers rotate about vertical axes to limit motion of said component along the axis of said first shaft.

7. An apparatus for applying cement to margins at opposite faces of a shoe component of differing thickness, said apparatus comprises a base, an electric motor fixed with respect to said base, a first journal fixed with respect to said base, a first shaft in said first journal and driven by said electric motor, a second journal constrained for motion with respect to said base in a first direction, a second shaft mounted for rotation in said second journal, said first shaft and said second shaft being disposed along horizontal axes, a universal coupling connecting said electric motor and said second shaft, a first cement wheel keyed to said first shaft, a second cement wheel keyed to said second shaft, a third journal constrained for motion with respect to said base in a second direction, a third shaft in said third journal, a third cement wheel keyed to said third shaft, a link fixedly connecting said second journal and said third journal, resilient means connected between said base and said link in order to urge said second cement wheel toward said first cement wheel, a first cement supply communicating with said first cement

wheel, a second cement supply communicating with said third cement wheel, said second cement wheel and said third cement wheel being geared together and in contact so that cement is transferred from said third cement wheel to said second cement wheel, whereby as said second cement wheel moves toward and away from said first cement wheel, the exposure of said third cement to said second cement supply is maintained constant, a support wheel mounted on said first shaft for free rotation in order to limit downward movement of said component, and a pair of guide rollers rotatable about substantially vertical axes to limit motion of said component along the axis of said first shaft.

10 8. The apparatus of claim 7 wherein the rate of flow of cement to said first cement wheel is determined by adjusting the exposure of said first cement wheel to said first cement supply.

15 9. The apparatus of claim 7 wherein the rate of flow of cement to said second cement wheel is determined by a skimming finger in contiguity with said second wheel.

20 10. The apparatus of claim 7 wherein downward motion of said second cement wheel and horizontal motion of said pickup wheel occur simultaneously.
